TYPEWRITER DESK

Charles M. Abrahamson, Aurora, Ill., assignor to All-Steel Equipment Inc., a corporation of Illinois

Application November 29, 1951, Serial No. 258,958

18 Claims. (Cl. 312—29)

The present invention relates to secretarial desks of the type provided with a disappearing typewriter compartment having means associated therewith for transferring the typewriter from a stored out-of-the-way, concealed position to an extended position for use.

More specifically the invention relates to a secretarial pedestal desk having an end pedestal providing an interior typewriter compartment having associated therewith a slidable carriage which is movable from a retracted position within the compartment to an extended position forwardly of the pedestal at one side of the desk, and having mounted thereon a typewriter-supporting shelf which is pivoted adjacent its back or rear edge to the carriage for swinging movement about a horizontal axis between a horizontal position for use in front of the pedestal and a vertical out-of-the-way position of alignment with the door opening of the compartment, whereby it may be moved bodily with the carriage into the compartment.

The objects of the invention are varied, and the invention, in one aspect thereof, is concerned with an efficient counterbalancing means for drop shelves of the type briefly outlined above, whether the drop shelf be associated with the movable carriage of a pedestal or other disappearing typewriter types of desk, or whether the drop shelf be associated with a stationary support. Accordingly, it is broadly an object of the invention to provide a novel type of counterbalancing mechanism for drop shelves of the type outlined above in which the varying gravitational torque applied to the drop shelf and the typewriter or other supported mass thereon, by virtue of the shifting of the center of gravity of the combined mass toward or away from the vertical plane passing through the axis of swinging movement of the drop shelf when moving the latter between its extreme positions, is effectively compensated for so that a more or less uniform yielding movement of the drop shelf in either direction throughout its entire range will result during manual shifting thereof.

The invention, in another aspect thereof is concerned with the centering or alignment of the extended drop shelf relative to the fore and aft direction of the desk and the prevention of shifting of the shelf after the same has attained its position of use. Accordingly, it is another object of the invention to provide a novel form of cooperating interlocking means between the drop shelf and the desk pedestal for aligning the shelf and holding the same securely in its extended position for use against lateral or angular shifting.

Yet another aspect of the invention, in a secretarial desk of the character outlined above, relates to a novel means for latching the drop shelf in either its lowered out-of-the-way position or in its elevated extended position of use. Accordingly, further objects of the invention are, in the former instance, to provide a novel form of cooperating latching mechanism on the drop shelf and on the supporting carriage therefor for releasably maintaining the drop shelf in its lower position

2

against the impelling action of the counterbalancing mechanism for the drop shelf, and in the latter instance, to provide a novel form of cooperating latching mechanism between the drop shelf and one side of the pedestal door opening for releasably maintaining the drop shelf in its elevated position of use.

Yet another object of the invention, in a desk of this character, is to provide a pedestal desk having a retractable drop shelf, typewriter-supporting, disappearing carriage which is movable into and out of the typewriter compartment through the door opening thereof, together with novel means for anchoring the hinged compartment door to the carriage when the latter is extended to prevent undesired movement of the open door as well as to lend a degree of rigidity to the extended carriage.

Other objects and advantages of the invention, not at this time enumerated, will become more readily apparent as the nature of the invention is better understood.

In the accompanying six sheets of drawings forming a part of this specification, one embodiment of the invention has been shown. In these drawings:

Fig. 1 is a perspective view of a pedestal desk constructed in accordance with the principles of the present invention and provided with a typewriter compartment having a retractable drop shelf construction associated therewith. In this view the drop shelf is shown in an extended position for use with a typewriter mounted thereon.

Fig. 2 is an enlarged fragmentary detail perspective view of one end of the desk showing the drop shelf in its lowered but extended position. In this view, the desk top has been removed to more clearly reveal the drop shelf supporting instrumentalities.

Fig. 3 is a fragmentary perspective view of one end of the desk taken from a location in front of and somewhat below the typewriter compartment. In this view, the typewriter supporting drop shelf is shown extended in its position of use.

Fig. 4 is an enlarged fragmentary front elevational view of an end of the desk looking directly into the typewriter compartment and showing the typewriter supporting drop shelf in its lowered but extended position. In this view certain parts have been broken away and other parts sectioned to more clearly reveal the nature of the invention.

Fig. 5 is a sectional view taken substantially along the line 5—5 of Fig. 4.

Fig. 6 is a sectional view taken substantially along the line 6—6 of Fig. 5.

Fig. 7 is a sectional view taken substantially along the plane indicated by the line 7—7 of Fig. 3 in the direction of the arrows, but with the drop shelf in its lowered position.

Fig. 8 is a sectional view taken substantially along the plane indicated by the line 8—8 of Fig. 3 in the direction of the arrows.

Figs. 9, 10, 11, 12 and 13 are detailed fragmentary side elevational views of the drop shelf counterbalancing mechanism employed in connection with the present invention and showing the same in progressively extended positions.

In all of the above described views, similar reference characters are employed to designate similar parts throughout.

Referring now to the drawings in detail, and particularly to Fig. 1, the improved drop shelf construction comprising the present invention is shown as being applied to a secretarial typewriter desk of the pedestal type in which the typewriter, when not in use, is concealed in a pedestal at one end of the desk. Pedestal desks of this character are commonly provided with a second pedestal at the opposite end of the desk for con-

taining office supplies, such as stationery, the opening between the pedestals affording knee room for the typist when the desk top is being used as a work space. It is to be distinctly understood, however, that the invention is not limited to use in connection with pedestal desks, and the same may be applied to other types of office desks or furniture having a typewriter compartment therein capable of accommodating the present drop shelf construction.

The pedestal desk of Fig. 1 involves in its general organization a desk top 19 supported by end pedestals 12 and 14 which are spaced apart to provide a clearance 16 affording knee room for the typist. The pedestal 12 is adapted to contain a bank of drawers 17. The pedestal 14 is adapted to enclose an internal typewriter compartment 18 within which the desk typewriter T is adapted to be stored in an out-of-the-way position when not in use. The compartment 18 is provided with an open front adapted to be closed with a hinged door panel 20 when the typewriter is in its stored position, a pair of offset hinge assemblies 21 (Fig. 3) being provided for supporting the door. A pair of supporting feet or pontoons 22 and 24 in the form of elongated channel-like members carry the entire weight of the desk including the pedestals 12 and 14 and serve to maintain the latter elevated from the floor.

The typewriter T is adapted to be positioned upon and carried by a retaining shelf or support 26 associated with the pedestal 14, and the present invention is directed, in the main, to the mechanism whereby the supporting shelf 26 is supported by the pedestal 14 for movement between an extended position of use and a retracted position wherein the shelf and typewriter supported thereon is wholly enclosed within the compartment 18 in an out-of-the-way position.

In the form of pedestal desk illustrated, the desk shelf or support 26 is of the drop leaf or drop shelf type, which is to say, it assumes a horizontal elevated position in front of the pedestal 14 at one end of the desk when extended for use, as shown in Fig. 1, and it assumes a vertical lowered position within the compartment 18 when retracted. During the transition period, while the drop shelf 26 is being moved from its extended to its retracted position, the shelf will assume a substantially vertical position shown in Fig. 2 wherein it is forward of the compartment prior to being slid rearwardly thereto upon the supporting carriage provided for it, and the nature and function of which will be set forth presently.

Reference to the "rear" edge of the desk shelf 26 and subsequent references to other portions thereof are absolute with respect to the shelf per se in relation to the normal position of the typewriter T when mounted thereon, while reference to portions of the desk structure other than the desk shelf are absolute with respect to the desk considered as a whole. Thus, the rear edge of the desk shelf is actually the left hand side edge of the shelf as viewed relative to the desk in Figure 1.

Referring now to Figs. 1, 2 and 4, the pedestal 14 of the desk includes outer and inner side walls 28 and 30 which are turned inwardly along their front edges as at 32 and 34 to provide a covering for a pair of corner frame posts 36 and 38, respectively. A lintel panel 40 extends across the upper ends of the posts 36 and 38, and a door sill beam 42 likewise extends between the posts at the bottom of the compartment 18. The posts 36 and 38 and beams 40 and 42 define therebetween the rectangular door opening of the compartment 18. The lintel beam 40 constitutes part of a shelf aligning or centering mechanism, the nature and function of which will be set forth presently. The pedestal 14 is also provided with a rear wall 43 and a bottom wall 44.

A gusset plate 45 at the upper right corner of the door opening (Fig. 8) carries a bumper pad 46 for the door 20 and a similar plate and bumper pad 48 and 50,

respectively, are provided at the lower right-hand corner of the door opening, as shown in Fig. 3.

5 A front rectangular frame 52 (Fig. 2) including top and bottom members 54 and 56, respectively, and side members 58 and 60 is secured within the compartment 18 adjacent the front opening thereof. A similar frame 62 (Figs. 4 and 7) is secured within the compartment 18 adjacent the rear wall thereof and includes top and bottom members 64 and 66 and side members, one of 10 which is shown at 68. The frame members 52 and 62 are suitably secured to the side walls of the pedestal 14, as by welding.

15 The vertical side members 58 and 68 of the frame members 52 and 62, respectively, constitute a rigid support for a pair of guide channels including an upper channel 70 (Figs. 2 and 4) and a lower channel 72 with the channels extending along the side wall 28 of the pedestal 14 inside the compartment 18. The guide channels 70 and 72 are spaced from the pedestal side wall 28 a distance equal to the width of the frame members 58 and 68.

20 The guide channels 70 and 72 are provided for the purpose of slidably supporting thereon a horizontally slidable carriage designated in its entirety at 74, and best illustrated in Fig. 3. The carriage 74 is in the form of a vertically disposed, generally flat plate 76 of rectangular design, except for the provision of a truncated corner 77 at the lower forward portion thereof. The carriage plate 76 is provided with a laterally downturned upper edge flange 30 78 (see also Fig. 2) having its outer edge turned downwardly as at 80. The plate 76 is formed with a laterally turned lower edge flange 82.

25 The horizontal slidable carriage 74 has hingedly secured thereto the drop shelf 26 by means of a pair of hinges 81 which are secured to the carriage plate 76 adjacent the front and rear upper corners thereof, and are secured to the underneath side of the drop shelf 26 adjacent the forwardly extending longitudinal edge thereof, as shown in Fig. 3.

30 40 The lower guide channel 72 includes a bottom flange 83 (Fig. 4) having an upturned edge 85 and an upper horizontal flange 87. The upper guide channel 70 (Fig. 2) is of wide channel construction and includes a back or trough member 84, a top flange or rail 86 and a bottom flange or rail 88 having a downturned flange 90 coextensive therewith. An intermediate angle rail 92 having a laterally and upwardly turned flange 94 is secured within the guide channel 70 and is substantially coextensive therewith.

35 45 The slidable carriage 74 has secured thereto a horizontally extending channel 95 (Fig. 4) which is coextensive with the carriage and which opposes the guide channel 70 when the carriage is retracted into the compartment 18. A forward weight-supporting roller 96 mounted on a stud 98 supported on the carriage 74 rests upon the horizontal bottom rail 83 of the channel 70 and serves in a large measure to support the combined weight of the carriage and the typewriter mounted thereon. A similar rear roller 100 (Fig. 2) is mounted on the carriage rearwardly of the roller 96 in horizontal alignment therewith and bears upwardly against and moves tractionally upon the underneath surface of the horizontal guide rail 94. This latter roller assimilates the upward thrust of the rear region of the carriage occasioned by 50 55 60 the weight of the typewriter and drop shelf acting downwardly on the carriage at a point forwardly of the weight supporting roller 96 which operates in the manner of a traveling fulcrum when the typewriter is mounted on the drop shelf 16 and when the latter is in its lowered vertical position. In other words, the unbalanced weight of the carriage, typewriter and drop shelf assembly about the axis of the roller 96 is assimilated by the roller 100 riding upwardly on the underneath side of the rail 94. A roller 102 carried on a horizontal stud 103 adjacent the 65 70 75 80 85 90 95 100 front end of the guide rail 70 extends into the channel

shaped member 95 and is adapted to bear against either the upper or the lower horizontal flange of the channel member 95 to assimilate any downward thrust of the carriage existing by virtue of the entire mass of the carriage, drop shelf and typewriter, or to assimilate any upward thrust exerted on the carriage, when the typewriter is removed from the drop shelf, existing by virtue of a spring loading counterbalancing mechanism associated with the drop shelf, and the nature and function of which will be made clear presently.

The slideable carriage 74 is guided against lateral thrust by means of a pair of spaced traveling thrust rollers 104, mounted on studs 106 carried on the lower flange of the channel member 95 and a thrust roller 108 mounted on a stud 110 carried on the top rail 86 of the channel member 70. The roller 103 is confined between the body of the carriage plate 76 and the downturned flange 89 formed thereon. At the bottom of the carriage 74 a pair of spaced traveling thrust rollers 110 mounted on the laterally turned flange 82 of the carriage are confined between the base of the channel member 72 and the upturned flange 85 thereof. An axially fixed roller 112 mounted on the laterally turned flange 87 of the channel member 72 cooperates with the side of the carriage plate 76 to assimilate the side thrust thereof.

As previously stated, the drop shelf 26 is movable relative to the carriage 74 to which it is hingedly secured between the lower position illustrated in Fig. 4 and the horizontal position illustrated in Fig. 3. The hinge assemblies 81 are secured to the underneath side of the drop shelf at longitudinally spaced points which are disposed forwardly from the edge 114 of the drop shelf 26 so that, when the drop shelf is in its elevated horizontal position, a portion thereof extending along the edge 114 may overlap the extended carriage assembly. The upper edge of the open door 20 projects above the plane of the drop shelf 26.

Referring now to Figs. 3 and 4, means are provided for releasably securing the forward or outer regions of the extended carriage plate 76 to the forward regions of the door panel 20 in order to lend a degree of support to the outer end of the carriage as well as to hold the door panel 20 against indiscriminate swinging movement relative to the drop shelf 26 when the latter is in its extended position of use. Toward these ends a locating pin 120 (see also Figs. 5 and 6) having an enlarged head 122 is suitably secured to the forward medial region of the door 20 on the inside thereof. A bracket 124 having an offset and bifurcated arm 126 is secured as at 127 to the opposing face of the carriage plate 76 near the forward region thereof, and the bifurcations of the arm 126 are adapted to straddle the shank portion of the locating pin 120 when the carriage is extended to the position shown in Figs. 3 and 5. A resilient keeper spring 128 bears against the head 122 of the locating pin 120 to take up any lost motion which may exist between the head of the pin and the bifurcated arm 126, thus safeguarding against side play of the door 20 when the parts are secured together in the manner described.

As previously stated, the drop shelf 26 is movable relative to the carriage 74, to which it is hingedly secured, between the position illustrated in Fig. 4 and the position illustrated in Fig. 3. As will be fully described subsequently, such movement between these two positions is accomplished by the compressional or expanding action of a yieldable counterbalancing spring leverage mechanism, including a spring proper 130, best illustrated in Fig. 4. Provision is also made whereby when the drop shelf assumes the lowered and substantially vertical position shown in Fig. 4, it may be latched securely to the carriage plate 76, and means are further provided whereby when the drop shelf 26 is in its horizontal extended position of use it may be latched in such position.

The means for latching the drop shelf 26 to the carriage plate 76 is best illustrated in Figs. 3 and 7 and

comprises a dog 132 which is suitably secured, as by welding, to the inner face of the carriage plate 76 in the medial rear regions thereof and having a latching shoulder 134 and an inclined cam surface 135 formed thereon. A latch housing 136 is riveted or otherwise secured to the underneath face of the drop shelf 26 adjacent the inner edge of the shelf and is provided with a rectangular entrance opening 138 designed for register with and reception of the dog 132 therein when the drop shelf 26 is swung to its lowered position. A movable latch plate 140 having a rectangular slot 142 therein is slideable in the housing 136 and is normally maintained in a potential latching position by means of a coil spring 144 secured at one end to a bracket 146 carried on the shelf 26 and at the other end to an operating bar 148 secured to the latch plate 140. The bar 148 extends along the underneath side of the drop shelf 26 in close proximity thereto to a point adjacent the forward edge thereof. A supporting bracket 150 serves to guide the forward end of the operating bar 148, and a manually engageable trip member 152 is secured to the bar 148 adjacent the free end thereof to permit tripping of the latch plate and release of the drop shelf 26 from its latched position. It will be understood that one edge of the slot 142 provided in the latch plate 140 is adapted to ride outwardly on the inclined cam surface 135 provided on the latching dog 132 to carry the edge of the slot 142 over the end of the shoulder 134 and into latching position behind the shoulder under the influence of the spring 144 when the drop shelf is forcibly moved to its lowered position.

The means for latching the drop shelf 26 in its elevated extended horizontal position of use is best illustrated in Figs. 3 and 8.

This means includes a latch member 154 pivotally mounted adjacent its lower end on a stud 156 extending horizontally across the front right-hand corner frame post 38 adjacent the upper regions thereof. The latch member 154 is partially concealed within the corner post 38 and is spring pressed as at 158 so as to partially project inwardly of the door opening through registering slots provided in the post. The inwardly projecting portion of the latch member 154 is provided with a shoulder 160 designed for latching engagement with an edge portion 162 of the drop shelf 26 when the latter is in its elevated position. The latch member 154 is movable from its advanced latching position as shown in Fig. 8 to a retracted position within the corner post 38 against the action of the spring 158. In order to move the latch to its retracted position so that the shoulder 160 thereof may clear the edge 162 of the drop shelf 26, a latch-retracting finger 164 is secured as at 166 to the medial regions of a lever arm 168 pivoted as at 170 to the underneath side of the drop shelf 26. The finger 164 normally occupies a position wherein its end lies in close proximity to the outer edge surface of the latch 154. A coil spring 172 has one end thereof secured to the latch member 164 and has its other end anchored to a bracket 174 suitable secured to the underneath side of the drop shelf 26. A manually operable release trip member 178 mounted on a link 180, pivotally connected as at 182 to the free end of the lever arm 168, occupies a position adjacent an inner corner of the drop shelf wherein it is conveniently accessible for manipulation. Transverse movement of the trip member 178 will impart movement to the lever 168 and latch releasing finger 164 so that the end of the latter will bear against the latch 154 and move the same to a retracted position wherein the shoulder thereof clears the edge 162 of the drop shelf 26 to permit downward swinging movement of the latter to its retracted position. It is obvious that upon movement of the drop shelf from its lowered position to its elevated position that the edge 162 of the drop shelf 26 will bear against the forward inclined edge of the latch member

154 and progressively retracting the same until such time as the edge 162 moves behind the shoulder 160, so that the drop shelf is thus latched in its extended position of use.

The drop shelf 26 as shown in Fig. 3 is in the form of a flat metal member having downwardly and inwardly turned marginal edges. A pair of longitudinally extending reinforcing members 184 and 186 extend along the underneath side thereof. The width of the typewriter supporting shelf proper is somewhat greater than the width of the door opening of the compartment 18, but the extreme inner regions of the drop shelf are of reduced width so that a small area of the drop shelf projects into the compartment and provides the latching edge 162 when the drop shelf is in its extended position of use. A handle 188 may be provided at the forward left-hand corner of the drop shelf 26 as viewed in Fig. 1 to facilitate movement of the carriage 74, together with the pivoted drop shelf 26, into and out of the compartment 18 when the drop shelf is in its lowered position.

In order to align the drop shelf 26 when in its extended horizontal position, as well as to lend rigidity thereto, a pair of spaced centering pins 189 carried at the outer edge of a flange 191 formed along the inner edge of the drop shelf is adapted to enter registering holes 193 provided in the door lintel panel 40 and beam 64. An L-bracket 192 (Figs. 2 and 8) is secured to the inside face of side member 58 of frame 52 and a bearing member 194 (Figs. 2 and 3) is secured to the rear marginal edge of shelf 26. When the shelf is in its horizontal position, L-bracket 192 contacts the top of shelf 26, as shown in Fig. 8, while member 194 contacts the rear edge of side member 58, as shown in Fig. 3. Entering pins 189 and member 194 will prevent substantial movement of shelf 26 in a horizontal plane while L-bracket 192, member 194, and latch member 154 will prevent substantial movement of shelf 26 in a vertical plane.

The counterbalancing and leverage mechanism for the drop shelf is best illustrated in Figs. 2, 3 and 4, and its principles of operation have been illustrated somewhat schematically in Figs. 9 to 12 inclusive. This counterbalancing and leverage mechanism is so designed as to act upon the combined mass of the drop shelf and the applied office machine or typewriter during movement of the drop shelf between its retracted and extended positions in such a manner that a more or less constant tension within reasonable limits is maintained for counterbalancing purposes. The previously mentioned spring 130 constitutes the sole force-applying means of the counterbalancing and leverage mechanism and the leverage system associated with the spring is such that when the spring is compressed to the maximum extent of which it is capable within the system, the leverage system exerts its least counterbalancing effect upon the drop shelf. This condition obtains when the shelf is in its lowermost position. When the drop shelf assumes its elevated position of use, the tension of the spring 130 may be nearly expended, but at this time the leverage system associated therewith exerts its maximum leverage effect upon the drop shelf. The action of the counterbalancing and leverage mechanism is predicated upon the fact that as the center of mass of the combined drop shelf and typewriter carried thereby shifts laterally outwardly away from the vertical plane of the carriage 76, the moment of torque applied to the drop shelf assembly due to gravity acting on the center of mass increases progressively. Thus the increments of counter-torque which must be applied to the drop shelf to just counterbalance the applied torque must be of an increasing nature so that, in the normal movement of the drop shelf toward its elevated position of use, a generally uniform application of manual torque to the drop shelf will effect such movement without sudden yielding of the drop shelf and without sudden resistance to motion. An adjustment is provided for the spring 130 which may conven-

iently be made to accommodate the varying weight of different typewriters which may be installed upon the drop shelf, and to provide the desired lift for the drop shelf.

Referring now to Fig. 3, the rear end of the carriage 74

5 has secured thereto a laterally extending, generally triangular back plate 200 which projects transversely of the compartment 18 and which is reinforced at its bottom by means of a triangular gusset plate 202. A lever arm 204 is pivotally secured as at 206 to the back plate 200 adjacent the lower left-hand corner thereof as viewed in Fig. 2, and projects upwardly and diagonally across the compartment 18 and carries at its free or swinging end a roller 208. A wedge-shaped bracket 210 (Figs. 2, 9 to 13 inclusive) is mounted on the rear or inner edge 212 of the drop shelf 26 and carries an elongated channel shape guide member 214 having inturned retaining flanges 216 and in which channel member the roller 208 is adapted to travel. The axis of the channel member 214 extends at a slight incline with respect to the plane of the drop shelf and the specific angularity of the channel axis is designed according to engineering exigencies so that certain principles of leverage existing between the coil spring 130 and the drop shelf will exist during swinging movement of the drop shelf, all in a manner that will become clear presently.

21 The coil spring 130 is mounted upon a guide rod 218 threadedly received in a socket member 220 pivoted as at 221 in a bracket 222 secured to the carriage plate 76 adjacent the rear lowermost corner thereof. The guide rod 218 projects outwardly through a slot 224 (Fig. 3) 22 provided in the carriage plate 76 and projects through the laterally turned end 226 of a link 228 secured as at 230 to the medial regions of the lever arm 204. The lower end of the spring 130 is centered within a cup member 232 threadedly received on the lower threaded end 234 of the guide rod 218 and the upper end thereof bears against a ferrule 236 slidably mounted on the guide rod 218 and bearing against the laterally turned end 226 of the link 228.

From the above description it will be seen that when the drop shelf 26 is in its vertical lowered position illustrated in Figs. 4 and 9, the roller 208 will occupy a position adjacent one end of the channel guide member 214, which is the upper end thereof. At this time the lever arm 204 will assume a position wherein the counterbalancing spring 130 is compressed to the fullest extent of which it is capable in the arrangement shown. With the parts in the position just described, the spring 130 acting through the link 228 will urge the lever arm 204 to swing in a counterclockwise direction as viewed in Fig. 9 and thus the roller 208 carried at the free swinging end of the lever 204 will be urged upwardly and to the left as viewed in Fig. 9 so as to in turn exert a leverage upon the drop shelf 26 and the mass of the typewriter carried thereon tending to swing the drop shelf in a clockwise direction so as to extend the shelf toward its raised position of use. Inasmuch as the drop shelf is in its latched position under the influence of the previously described latching mechanism including the latch dog 132 and latch plate 140, the drop shelf is maintained immobile, however, as soon as the latch mechanism is released in the manner previously described, the leverage exerted by the roller 208 on the drop shelf 26 may take effect and swinging movement of the drop shelf upwardly will commence. The extent of this leverage applied by the roller 208 to the drop shelf 26 is, however, relatively small since the compound leverage system acting thereon consists of two compounded third-class lever actions. Such a leverage action conforms to the principles of the present invention in that the center of gravity of the drop shelf and attached typewriter is 50 relatively close to the vertical plane of the axis of the hinges 81 of the drop shelf 26. The rate of the spring 130 is such that when it is fully compressed as shown in Fig. 9 with the drop shelf 26 being substantially vertical, the compound third-class lever action exerted upon the drop shelf is just sufficient to overcome the gravitational torque

applied to the drop shelf tending to maintain the same in its vertical position.

In Fig. 10, the drop shelf 26 has been moved to a position wherein it makes an angle of substantially 30° with the vertical plane of the carriage plate 76. In this position, the center of gravity of the drop shelf and its attached typewriter has moved outwardly to an extent proportional to the sine of the angle subtended between the planes of the drop shelf and the vertical plane of the carriage plate 76 so that the gravitational torque applied to the drop shelf is substantially greater. To counterbalance this added torque effect, the roller 208 has moved inwardly from the upper end of the channel member 214 a slight distance so that the compound third-class lever actions applied to the drop shelf have increased. Due to the fact that lever arm 204 is approaching a position which is normal to the axis of the guide rod 218, the first third-class leverage component of the compound system is slightly increased due to the fact that the roller 208 has moved farther away from the axis of the hinges 81. The second leverage component of the compound system has also increased. The net result is that the product of these two leverage components is materially greater. In this position of the drop shelf 26, the rate of the spring 130 and the extent of the leverage action exerted thereby on the drop shelf are again just sufficient to overcome the gravitational torque applied to the shelf and typewriter assembly so that the tendency of the latter still is to swing upwardly toward the extended position of the drop shelf.

In Figs. 11 and 12 the positions of the various components of the leverage system are illustrated when the drop shelf 26 assumes a 45° and a 60° angle with respect to the vertical plane of the hinge axis. In each instance both components of the dual compound third-class leverage system increase so that the product thereof rapidly increases the torque applied to the drop shelf tending to elevate the same. As the drop shelf 26 continues to move upwardly, the roller 208 moves farther away from the horizontal axis of the hinges 81, thereby increasing the extent of the compound leverage action not only to account for the outward shifting of the center of gravity of the mass of the typewriter and drop shelf, but also to account for the decrease in force applied to the link 228 by the progressively expanding compression spring 130. At any given angular position of the drop shelf 26, the rate of the spring 130 and the extent of the leverage exerted by the roller 208 on the wall of the channel member 214 is such as to just overcome the effect of gravitational torque acting on the drop shelf 26 and the typewriter mounted thereon.

In Fig. 13 the drop shelf 26 is illustrated in the position it will assume just prior to becoming horizontal and immediately before the edge 162 of the shelf (Figs. 3 and 8) trips the latch 154 and moves over the shoulder 160 thereof. In this position of the drop shelf 26, the roller 208 has moved to the left-hand end of the channel member 214 as viewed in Fig. 13, so that a relatively powerful compound leverage action, involving the link 228 and lever arm 204 as the first component and involving the roller 204 and channel member 214 as the second component, is exerted on the drop shelf tending to move the same to its final horizontal latched position. Although the force existing in the spring 130 may be nearly expended, the extent of the compound leverage action is such as to move the drop shelf to its final position against the increased gravitational torque exerted on the drop shelf and article carried thereby. It will be seen that by rotating the cup member 232 on the threaded portion 234 of the guide rod 218 so as to move the member axially along the guide rod 218, the effective rate of the spring 130 may be varied to accommodate typewriters having different weights.

The invention is not to be limited to the exact arrangement of parts shown in the accompanying drawings and

described in this specification, as various changes in the details of construction may be resorted to without departing from the spirit of the invention. For example, while the improved counterbalancing mechanism of the present invention is shown as being applied to a drop shelf associated with the movable carriage of a pedestal desk typewriter compartment, the counterbalancing mechanism may be found useful, with or without modification, for counterbalancing the weight of drop shelves designed to support objects other than typewriters, as for example sewing machines and machines other than those designed for office or household use. The counterbalancing mechanism may be used in connection with stationary supports as well as with sliding, disappearing carriages of the type illustrated herein. Only insofar as the invention has been particularly pointed out in the accompanying claims is the same to be limited.

I claim:

1. A supporting structure for typewriters and the like comprising a support, a typewriter-supporting drop shelf pivoted adjacent its rear edge to said support and movable from a substantially horizontal operative position, by a swinging action about a horizontal axis, downwardly to an approximately vertical out-of-the-way lowered position, and instrumentalities for counterbalancing the weight of said drop shelf and the typewriter mounted thereon comprising a member mounted on and movable bodily with the drop shelf and providing an elongated guideway extending generally in the fore and aft direction of the drop shelf, a lever arm having one end pivoted to said support below the level of the drop shelf when extended and about an axis spaced forwardly from the vertical plane of the drop shelf when in its out-of-the-way position, a follower carried at the free end of said lever arm and confined in said guideway, and spring means normally urging said lever arm about the pivotal axis thereof in a direction whereby said follower is constrained to move forwardly in said guideway.

2. A supporting structure for typewriters and the like comprising a support, a typewriter-supporting drop shelf pivoted adjacent its rear edge to said support and movable from a substantially horizontal operative position, by a swinging action about a horizontal axis, downwardly to an approximately vertical out-of-the-way lowered position, and instrumentalities for counterbalancing the weight of said drop shelf and the typewriter mounted thereon comprising a member mounted on and movable bodily with the drop shelf and providing an elongated guideway extending generally in the fore and aft direction of the drop shelf, a lever arm having one end pivoted to said support below the level of the drop shelf when extended and about an axis spaced forwardly from the vertical plane of the drop shelf when in its out-of-the-way position, a follower carried at the free end of said lever arm and confined in said guideway, and a spring having one end effectively bearing against said support and its other end effectively bearing against said lever arm at a point medially thereof and normally urging said lever arm about the pivotal axis thereof in a direction whereby said follower is constrained to move forwardly in said guideway.

3. A supporting structure for typewriters and the like comprising a support, a typewriter-supporting drop shelf pivoted adjacent its rear edge to said support and movable from a substantially horizontal operative position, by a swinging action about a horizontal axis, downwardly to an approximately vertical out-of-the-way lowered position, and instrumentalities for counterbalancing the weight of said drop shelf and typewriter mounted thereon comprising a member mounted on and movable bodily with the drop shelf and providing an elongated guideway forwardly of said axis and extending generally in a fore and aft direction relative to the drop shelf, a lever arm having one end pivoted to said support below the level of the drop shelf when extended

and about an axis spaced forwardly from the vertical plane of the drop shelf when in its out-of-the-way position, a follower carried at the free end of said lever arm and confined in said guideway, and spring means normally urging said lever arm about the pivotal axis thereof in a direction whereby said follower is constrained to move forwardly in said guideway.

4. A supporting structure for typewriters and the like comprising a support, a typewriter-supporting drop shelf pivoted adjacent its rear edge to said support and movable from a substantially horizontal operative position, by a swinging action, about a horizontal axis, downwardly to an approximately vertical out-of-the-way lowered position, and instrumentalities for counterbalancing the weight of said drop shelf and typewriter mounted thereon comprising a member mounted on and movable bodily with the drop shelf and providing an elongated guideway extending generally in a fore and aft direction relative to the drop shelf, a lever arm having one end pivoted to said support below the level of said horizontal axis at a point spaced forwardly from said axis, a follower carried at the free end of said lever arm and confined in said guideway, a spring having one end effectively bearing against said support and its other end effectively bearing against said lever arm at a point medially thereof and normally urging said lever arm about the pivot point thereof in a direction whereby said follower is constrained to move forwardly in said guideway, and means for varying the effective rate of said spring to accommodate the weight of different typewriters mounted on said drop shelf.

5. A supporting structure for typewriters and the like comprising a support, a typewriter-supporting drop shelf pivoted adjacent its rear edge to said support and movable from a substantially horizontal operative position, by a swinging action about a horizontal axis, downwardly to an approximately vertical out-of-the-way lowered position, and instrumentalities for counterbalancing the weight of said drop shelf and typewriter mounted thereon comprising a member mounted on and movable bodily with the drop shelf and providing an elongated guideway forwardly of said axis and extending generally in a fore and aft direction relative to the drop shelf, a lever arm having one end pivoted to said support below the level of the drop shelf when extended and about an axis spaced forwardly from the vertical plane of the drop shelf when in its out-of-the-way position, a follower carried at the free end of said lever arm and confined in said guideway, a guide rod pivotally secured to said support for swinging movement about a horizontal axis adjacent the vertical plane of the drop shelf when in its vertical position and projecting forwardly therefrom, a thrust member mounted on said guide rod adjacent its pivoted end, a compression spring surrounding said guide rod and bearing at one end against said thrust member and effectively bearing at the other end against said lever arm in the medial regions thereof for normally urging said lever arm about the pivotal axis thereof in a direction whereby said follower is constrained to move forwardly in said guideways.

6. A supporting structure for typewriters and the like comprising a support, a typewriter-supporting drop shelf pivoted adjacent its rear edge to said support and movable from a substantially horizontal operative position, by a swinging action about a horizontal axis, downwardly to an approximately vertical out-of-the-way lowered position, and instrumentalities for counterbalancing the weight of said drop shelf and typewriter mounted thereon comprising an elongated channel member mounted on and movable bodily with the drop shelf and having one end thereof positioned adjacent said horizontal axis and its other end positioned adjacent the forward edge of the drop shelf, a lever arm having one end pivoted to said support below the level of the drop shelf when extended and forwardly of the vertical plane passing through said

axis, a follower roller mounted on the free end of said lever arm and confined in said channel member, the length of said lever arm being such that the roller assumes a position within said channel member adjacent one end thereof when the drop shelf is in its vertical lowered position and adjacent the other end of the channel member when the drop shelf is in its horizontal operative position, and spring means normally urging said lever arm in a direction whereby said follower is constrained to move forwardly in said channel member, said spring means and lever arm being constructed and arranged whereby the maximum counter-torque applied to the drop shelf to overcome the weight of the drop shelf and its load occurs when the drop shelf is adjacent horizontal position.

7. A supporting structure for typewriters and the like comprising a support, a typewriter-supporting drop shelf pivoted adjacent its rear edge to said support and movable from a substantially horizontal operative position, by a swinging action about a horizontal axis, downwardly to an approximately vertical out-of-the-way lowered position, and instrumentalities for counterbalancing the weight of said drop shelf and typewriter mounted thereon comprising an elongated channel member mounted on and movable bodily with the drop shelf and having one end thereof positioned adjacent said horizontal axis and its other end positioned adjacent the forward edge of the drop shelf, a lever arm having one end pivoted to said support below the level of the drop shelf when extended and forwardly of the vertical plane passing through said axis, a follower roller mounted on the free end of said lever arm and confined in said channel member, the length of said lever arm being such that the roller assumes a position within said channel member adjacent one end thereof when the drop shelf is in its vertical lowered position and adjacent the other end of the channel member when the drop shelf is in its horizontal operative position, and a spring having one end effectively bearing against said support and its other end bearing against said lever arm at a point medially thereof and normally urging said lever arm in a direction whereby said follower is constrained to move forwardly in said channel member, said spring and lever arm being constructed and arranged whereby the maximum counter-torque applied to the drop shelf to overcome the weight of the drop shelf and its load occurs when the drop shelf is adjacent horizontal position.

8. A supporting structure for typewriters and the like comprising a support, a typewriter-supporting drop shelf pivoted adjacent its rear edge to said support and movable from a substantially horizontal operative position, by a swinging action about a horizontal axis, downwardly to an approximately vertical out-of-the-way lowered position, and means for counterbalancing the weight of the drop shelf and the typewriter mounted thereon comprising a compound leverage system including a third-class lever fulcrumed on said support below the drop shelf pivot and having a force applying end, means providing a second third-class lever fulcrumed about said horizontal axis, said first lever having its force-applying end in slidible engagement with said second lever to vary the point of application of force from the first lever to the second lever and yieldable means for applying power to said first lever.

9. A supporting structure for typewriters and the like comprising a support, a typewriter-supporting drop shelf pivoted adjacent its rear edge to said support and movable from a substantially horizontal operative position, by a swinging action about a horizontal axis, downwardly to an approximately vertical out-of-the-way lowered position, and instrumentalities for counterbalancing the weight of said drop shelf and typewriter mounted thereon comprising an elongated channel member mounted on and movable bodily with the drop shelf and having one end thereof positioned adjacent said horizontal axis and its other end positioned adjacent the forward edge of the

drop shelf, a lever arm having one end pivoted to said support below the level of the drop shelf when extended and forwardly of the vertical plane passing through said axis, a follower roller mounted on the free end of said lever arm and confined in said channel member, the length of said lever arm being such that the roller assumes a position within said channel member adjacent one end thereof when the drop shelf is in its vertical lowered position and adjacent the other end of the channel member when the drop shelf is in its horizontal operative position, a guide rod having a threaded end pivotally secured to said support, a thrust member threadedly received on said guide rod, a link secured to said lever arm medially thereof and through which said guide rod slidably extends and a compression spring surrounding said guide rod and bearing at one end against said thrust member and at the other end against said link and normally urging said lever arm about the pivotal axis thereof in a direction whereby said roller is constrained to move forwardly in said channel member.

10. In a device of the character described, a desk provided with a pedestal, a carriage slideable in said pedestal between a retracted position wherein it is wholly contained within the pedestal to an advanced position wherein it is projected therefrom, a drop shelf pivoted adjacent its rear edge to said carriage and movable from a substantially horizontal operative position, by a swinging action about a horizontal axis, downwardly to an approximately vertical out-of-the-way lowered position, and instrumentalities for counterbalancing the weight of said drop shelf and an article supported thereon comprising a member mounted on and movable bodily with the drop shelf and providing an elongated guideway extending generally in the fore and aft direction of the shelf, a lever arm having one end pivoted to said carriage below the level of said axis and forwardly thereof, a follower carried at the free end of said lever arm and confined in said guideway and a spring having one end effectively bearing against said carriage and its other end effectively bearing against said lever arm medially thereof and normally urging the latter about the pivotal axis thereof in a direction whereby said follower is constrained to move forwardly in said guideway, said spring and lever being constructed and arranged whereby the countertorque applied to the drop shelf to overcome the weight of the drop shelf and its load substantially equals or exceeds the torque of said drop shelf and load at any given angular position of the drop shelf.

11. A desk provided with a pedestal having inner and outer side walls, a carriage slideable in said pedestal between a retracted position wherein it is wholly contained within the pedestal and an advanced position wherein it is projected therefrom, a drop shelf pivotally mounted adjacent its rear edge to the upper regions of said carriage for swinging movement about a horizontal axis from a horizontal position of use to a vertical lowered position, instrumentalities for counterbalancing the weight of said drop shelf and the typewriter mounted thereon comprising a lever pivoted to said carriage at one end at a point spaced forwardly from the vertical plane of the drop shelf when in its lowered position and having its other end slidably connected to the drop shelf, spring means normally urging said lever about its pivot in a direction to cause the other end of said lever to move forwardly along said drop shelf, said counterbalancing means normally urging said drop shelf to its horizontal extended position, cooperating releasable latch means on said carriage and drop shelf for securing said drop shelf in its lowered position, and cooperating releasable latch means on said drop shelf and pedestal for securing said drop shelf in its horizontal position.

12. A typewriter desk having an end pedestal provided with inner and outer side walls and enclosing a typewriter compartment therein, the forward end of said pedestal being provided with a door opening communica-

cating with said compartment and having a lintel beam, a carriage comprising a substantially vertical plate slideable horizontally into and out of said compartment adjacent the outer side wall of the pedestal, a typewriter supporting drop shelf pivoted adjacent its rear edge to the upper regions of said carriage plate and movable from a substantially horizontal operative position, by a swinging action about a horizontal axis, downwardly to an approximately vertical lowered position, instrumentalities for counterbalancing the weight of said drop shelf with a typewriter mounted thereon, said drop shelf being provided with a typewriter supporting surface of a width greater than the transverse width of said door opening and being provided with an end region of a width less than the width of said door opening, said latter region of the drop shelf directly underlying said lintel beam when the carriage is extended and the drop shelf is in its horizontal operative position, and cooperating centering means on said lintel beam and the underlying portion of said drop shelf for aligning said drop shelf relative to said pedestal in all horizontal directions when the drop shelf is in its horizontal position said cooperating centering means including a tapered pin and a mating opening, one being associated with the lintel beam and the other with said drop shelf.

13. A supporting structure for typewriters and the like comprising a support, a typewriter-supporting drop shelf pivoted adjacent its rear edge to said support and movable from a substantially horizontal operative position, by a swinging action about a horizontal axis, downwardly to an approximately vertical out-of-the-way lowered position, and instrumentalities for counterbalancing the weight of said drop shelf and the typewriter mounted thereon comprising a member mounted on and movable bodily with the drop shelf and providing an elongated guideway forwardly of said axis and extending generally in the fore and aft direction of the drop shelf, a lever arm having one end pivoted to said support below the level of the drop shelf when extended and about an axis spaced forwardly from the vertical plane of the drop shelf when in its out-of-the-way position, a follower carried at the free end of said lever arm and confined in said guideway, and a spring having one end effectively bearing against said support and its other end effectively bearing against said lever arm at a point medially thereof and normally urging said lever arm about the pivotal axis thereof in a direction whereby said follower is constrained to move forwardly in said guideway.

14. A supporting structure for typewriters and the like comprising a support, a typewriter-supporting drop shelf pivoted adjacent its rear edge to said support and movable from a substantially horizontal operative position, by a swinging action about a horizontal axis, downwardly to an approximately vertical out-of-the-way lowered position, and instrumentalities for counterbalancing the weight of said drop shelf and the typewriter mounted thereon comprising a lever arm having one end pivoted to said support below the level of the drop shelf when extended and about an axis spaced forwardly from the vertical plane of the drop shelf when in its out-of-the-way position and having a force applying end, a member movable bodily with the drop shelf and extending generally in the fore and aft direction of the drop shelf, said lever arm having its force-applying end in slidable engagement with said member to vary the point of application of force from the lever arm to said member, and a spring having one end effectively bearing against said lever arm at a point medially thereof and normally urging said lever arm about the pivotal axis thereof in a direction whereby the force-applying end of said lever arm is constrained to move forwardly along said member.

15. A supporting structure for typewriters and the like comprising a support, a typewriter-supporting drop shelf pivoted adjacent its rear edge to said support and movable from a substantially horizontal operative position, by a

swinging action about a horizontal axis, downwardly to an approximately vertical out-of-the-way lowered position, and instrumentalities for counterbalancing the weight of said drop shelf and the typewriter mounted thereon comprising a lever arm having one end pivoted to said support below the level of the drop shelf when extended and about an axis spaced forwardly from the vertical plane of the drop shelf when in its out-of-the-way position and having a force applying end, a member movable bodily with the drop shelf and extending generally in the fore and aft direction of the drop shelf, said lever arm having its force-applying end in slidable engagement with said member to vary the point of application of force from the lever arm to said member, and spring means normally urging said lever arm about the pivotal axis thereof in a direction whereby the force-applying end of said lever arm is constrained to move forwardly along said member.

16. A supporting structure for typewriters and the like comprising a support, a typewriter-supporting drop shelf pivoted adjacent its rear edge to said support and movable from a substantially horizontal operative position, by a swinging action about a horizontal axis, downwardly to an approximately vertical out-of-the-way lowered position, and instrumentalities for counterbalancing the weight of said drop shelf and the typewriter mounted thereon comprising a lever arm having one end pivoted to said support below the level of the drop shelf when extended and about an axis spaced forwardly from the vertical plane of the drop shelf when in its out-of-the-way position and having a force applying end, a member movable bodily with the drop shelf and extending generally in the fore and aft direction of the drop shelf, said lever arm having its force-applying end in slidable engagement with said member to vary the point of application of force from the lever arm to said member, and a spring having one end effectively bearing against said lever arm at a point medially thereof and normally urging said lever arm about the pivotal axis thereof in a direction whereby the force-applying end of said lever arm is constrained to move forwardly along said member, said spring means and lever arm being constructed and arranged whereby the maximum counter-torque applied to the drop shelf to overcome the weight of the drop shelf and its load occurs when the drop shelf is adjacent its horizontal position.

17. A typewriter desk having an end pedestal provided with inner and outer side walls and enclosing a typewriter compartment therein, the forward end of said pedestal being provided with a door opening communicating with said compartment and having a lintel beam member, a carriage comprising a substantially vertical plate slidable horizontally into and out of said compartment adjacent the outer side wall of the pedestal, a typewriter supporting drop shelf member pivoted adjacent its rear edge to the upper regions of said carriage plate and movable from a substantially horizontal operative position, by swinging

action about a horizontal axis, downwardly to an approximately vertical lowered position, instrumentalities for counterbalancing the weight of said drop shelf member with a typewriter mounted thereon, said drop shelf member being provided with a typewriter supporting surface of a width greater than the transverse width of said door opening and being provided with an end region of a width less than the width of said door opening, said latter region of the drop shelf member directly underlying said lintel beam member when the carriage is extended and the drop shelf member is in its horizontal operative position, and spaced centering pins provided on one of said members and cooperating with spaced holes formed in the other of said members to align said drop shelf member relative to said pedestal in all horizontal directions when the drop shelf member is in its horizontal position.

18. A typewriter desk having an end pedestal provided with inner and outer side walls and enclosing a typewriter compartment therein, the forward end of said pedestal being provided with a door opening communicating with said compartment and having a lintel beam, a carriage comprising a substantially vertical plate slidable horizontally into and out of said compartment adjacent the outer side wall of the pedestal, a typewriter supporting drop shelf pivoted adjacent its rear edge to the upper regions of said carriage plate and movable from a substantially horizontal operative position, by a swinging action about a horizontal axis, downwardly to an approximately vertical lowered position, instrumentalities for counterbalancing the weight of said drop shelf with a typewriter mounted thereon, said drop shelf being provided with a typewriter supporting surface of a width greater than the transverse width of said door opening and being provided with an end region of a width less than the width of said door opening, said latter region of the drop shelf directly underlying said lintel beam when the carriage is extended and the drop shelf is in its horizontal operative position, and spaced centering pins on the underlying portion of said drop shelf cooperating with spaced holes formed in said lintel beam for aligning said drop shelf relative to said pedestal in all horizontal directions when the drop shelf is in its horizontal position.
